Primary Examiner — Mark A Goodwin(74) *Attorney, Agent, or Firm* — Renner, Otto, Boisselle & Sklar, LLP(57) **CLAIM**

The ornamental design for a hopper lid, as shown and described.

DESCRIPTION

FIG. 1 is a top, front, right perspective view of a hopper lid showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line showing in FIGS. 1-7 is for the purpose of illustrating portions of the hopper lid and forms no part of the claimed design.
